UNITED STATES PATENT OFFICE.

CLARENCE A. MENTZER, OF MINNEAPOLIS, MINNESOTA, ASSIGNOR TO STOCKLAND ROAD MACHINERY COMPANY, OF MINNEAPOLIS, MINNESOTA, A CORPORATION.

ROAD-GRADING MACHINE.

Application filed January 7, 1926. Serial No. 79,743.

My invention relates to road grading machines, and an object is to provide a counter-balancing device in combination with the means for raising and lowering the scraper blade so that the weight of the latter and parts which raise and lower therewith, will be substantially counterbalanced for all vertical positions of the scraper blade whereby manipulation thereof may be very easily 5 performed by the operator.

The full objects and advantages of my invention will appear in connection with the detailed description thereof, and the novel features of my inventive idea will be particularly pointed out in the claims.

In the accompanying drawings which illustrate a practical embodiment of my invention,—

Fig. 1 is a plan view of a standard reversible road grading machine embodying the principles of the present invention. Fig. 2 is a view on an enlarged scale in vertical section on the line 2—2 of Fig. 1. Fig. 3 is a view in horizontal section on the line 3—3 of Fig. 2. Fig. 4 is a view similar to Fig. 2 showing some of the parts in a different position. Fig. 5 is a view in vertical section on the line 5—5 of Fig. 3. Fig. 6 is a side elevational view of the rear portion of the machine. Fig. 7 is a view on an enlarged scale in section on the line 7—7 of Fig. 2. Fig. 8 is a view on an enlarged scale in section on the line 8—8 of Fig. 2.

The machine includes a front axle 10 upon which wheels 12 are mounted and a rear axle 14 upon which wheels 16 are mounted. A platform 18 is supported by the rear axle. Upwardly inclined supports 20 extend forwardly from the platform 18 and connect it to the rear ends of longitudinal frame members 22 and 24 which are integrally united at their front ends slightly ahead of the front axle 10. A cross bar 26 positioned above the axle 10 connects the members 22 and 24. A scraper blade 28 is carried by a pair of arms 30 which are secured to diametrically opposite projections 32 extending out from a ringlike member 34 having a downwardly extending flange 36 around its periphery as shown in Fig. 2. The ringlike member 34 is rotatably supported due to the fact that its inner margin fits into recesses of ears 38 carried by angle members 40 to which are secured the rear ends of a pair of bars 42 which converge

toward the front and are secured to a short draw bar 44 which is pivotally connected with the cross bar 26 at its middle. The scraper blade is, therefore, drawn from the cross bar 26 at the front of the machine and 60 it may be swung in a horizontal plane so as to vary its inclination in such plane by rotating the ring member 34 in customary manner. As will be understood, the lower face of the ring 34 has an annular rack 46 65

which is engaged in the usual manner for operation by a shaft 48 extending rearwardly to a position in reach of the operator, this shaft lying underneath a shaft 50 which extends forwardly and has operative connections with the front axle for steering purposes. The ring 34 is provided on its inner margin with a circle of notches 52, different ones of which may be engaged in the usual manner by a locking bolt according to the 70

angular position of the scraper blade and which bolt may be withdrawn from its locking engagement by a rod 54 extending rearwardly to a position in reach of the operator. Toward their rear ends the bars 42 are connected by a cross bar 56 and have brackets 58 extending outwardly. Links 60 are pivotally attached at their lower ends to the outer ends of the brackets 58 and at their upper ends are pivoted to crank arms 62 75 formed at the forward ends of shafts 64 mounted in bearings formed in the upper ends of standards 66 extending up from the frame members 22 and 24. The rear end portions of the shafts 64 extend through 80 bearings 68 into worm gear casing 70 carried by standards 72 extending up from the supports 20. The standards 72 are reinforced by a plate 74 secured thereto and also secured to the upper ends of the supports 20. The shafts 64 are operated by hand wheels 76 secured to shafts 78 whose inner ends are connected to the rear ends 85 of the shafts 64 by worm gears contained in the casings 70. It is obvious that the worm gears act in the usual way as locks to hold the scraper blade in the vertical position in which it is set by turning the wheels 76 in one direction or the other according to 90

the vertical position desired for the scraper blade. The parts thus far described are or may be of well known construction. It is obvious that with such construction, a considerable effort on the part of the operator is required to lift the scraper blade. It is 100 105 110

also obvious that if an ordinary spring arrangement were employed which would counterbalance the weight of the scraper blade when in raised position, then a considerable effort would be required to depress the scraper blade to lower position against the tension of the springs and there would always be a tendency for the springs to lift the scraper blade into its highest position.

5 The construction now to be described provides for counter-balancing the scraper blade regardless of its vertical position. Two springs 80 are secured at their forward ends to nut members 82 in the manner best shown in Fig. 2. Screw threaded rods 84 are turned into the nut members 82 and secured in adjusted position by lock nuts 86. The forward ends of the rods 84 have heads 88 which are held by bracket members 90 secured to the cross bar 26. The rear ends of the springs 80 are secured to nut members 92 which are connected by coupling members 94 with chains 96 whose rear ends are secured by bolts 97 to sheaves 98 having annular grooves 99 to receive the chains. Curved arms 100 are secured to and preferably cast integrally with one of the sides of each of the sheaves 98. The arms 100 in the embodiment shown extend for substantially a semicircumference and have chain-receiving grooves 101. These arms as will be apparent from Figs. 2 and 4 have their inner ends determined by the radius of the sheaves and the arms are made on a larger curve than the sheaves and are outwardly and gradually deflected therefrom so that their outer ends are located quite an appreciable distance from the periphery of the sheaves. Each combined sheave and arm is mounted on a shaft 102, the ends of which are mounted in bearings 104 secured to the upper sides of the frame members 22 and 24. The upper ends of chains 106 are secured to the outer ends of the arms 100 by bolts 108 and the lower ends of these chains are attached to bolts 110 which connect the ends of two spaced bars 112 and 114 which in effect constitute a compound bar. Referring again to the angle members 40 it will be seen that they have flanges 116 which are connected by a cross bar 118 secured by bolts 120 which pass through the end portions of the bar 118 and also pass through outturned end flanges 122 of a bar 124 which is bent twice at right angles on each side of its middle. The spaced bars 114 and 116 are mounted at their middle on a bolt 126 which passes through the middle of the bars 118 and 124.

60 The operation and advantages of my invention will be readily understood in connection with the foregoing description. When the hand wheels 76 are turned to cause the crank arms 62 to extend upwardly as shown in Fig. 6, the scraper blade will be

brought into raised position. At this time, the contraction of the springs 80 will have caused the sheaves 98 to rotate and bring the chains 96 and 106 into the position shown in Fig. 2 whereby the leverage or turning moment exerted by the arms 100 and the chains 106 due to the weight of the parts suspended therefrom is practically counteracted. When the handwheels 76 are turned in a direction to lower the scraper blade, the springs 80 will be gradually stretched and the leverage or turning moment exerted by the arms 100 and chains 106 on the sheaves 98 will gradually increase due to the fact that the arms 100 are moved from one side of the shaft 102, over the same and then extend outwardly at the other side thereof as shown in Fig. 4. This increasing leverage in one direction compensates for the increasing tension exerted in the other direction by the springs so that substantially constant counterbalancing is produced regardless of the vertical position of the scraper blade. In other words, the weight of the scraper blade and parts which raise and lower therewith, will be neutralized for all vertical positions of the scraper blade. The strength of the springs and the construction of the curved arms are so correlated that this result is accomplished. Proper adjustment of the springs may be readily made by means of the screw rods 84 and lock nuts 86. It is obvious that with this construction, very little effort is required on the part of the operator to raise and lower the scraper blade since the worm gearing which produces this result may be very easily turned.

I claim:

1. In a road grading machine, the combination of a scraper support, means for raising and lowering said support, a shaft carried by the frame of the machine, a sheave mounted on said shaft, a curved arm eccentrically mounted with relation to said shaft for turning movement in unison with said sheave, a flexible member secured at one end to said support and secured at the other end to the outer end of said arm for winding movement on the latter, a flexible member secured to said sheave for winding movement thereon reversely to the winding movement of said first flexible member, and a spring attached to the outer end of said second flexible member.

2. In a road grading machine, the combination of a scraper support, means for raising and lowering said support, a shaft carried by the frame of the machine, a combined sheave and arm mounted on said shaft, said arm being curved and disposed eccentrically with relation to said shaft, a flexible member secured at one end to said support and secured at the other end to the outer end of said arm for winding movement on the

latter, a flexible member secured to said sheave for winding movement thereon, reversely to the winding movement of said first flexible member, and a spring attached 5 to the outer end of said second flexible member.

3. In a road grading machine, the combination of a scraper support, means for raising and lowering said support, a shaft carried by the frame of the machine, a sheave mounted on said shaft, a curved arm eccentrically mounted with relation to said shaft for turning movement in unison with said sheave, a flexible member secured at one end 10 to said support and secured at the other end to the outer end of said arm for winding movement on the latter, a flexible member secured to said sheave for winding movement thereon reversely to the winding movement 15 of said first flexible member, a coiled spring attached at one end to the outer end of said second flexible member, a nut member to which the other end of said spring is attached, and a screw threaded rod held at 20 one end and threaded through said nut member.

4. In a road grading machine, the combination of a scraper support, means for raising and lowering said support, a shaft carried by the frame of the machine, a combined sheave and arm mounted on said shaft, said arm being curved and disposed eccentrically with relation to said shaft, said 25

sheave and arm having grooves in their peripheries, a bolt secured to the outer end of 30 said arm, a flexible member connecting said support and bolt and arranged to have a winding movement in the groove of said arm, a bolt secured to said sheave substantially 180° from said first bolt, a flexible 35 member secured to said second bolt and arranged to have winding movement in the groove of said sheave reversely to the winding movement of said first flexible member, and a spring attached to the outer end of 40 said second flexible member.

5. In a road grading machine, the combination of a scraper support, means for raising and lowering said support, a transverse shaft carried by the frame of the machine, a 45 pair of combined sheaves and arms mounted on said shaft, said arms being curved and disposed eccentrically with relation to said shaft, a cross bar pivoted at its center on said support, flexible connections between 50 the ends of said cross bar and the outer ends of said arms and arranged to have a winding movement on the latter, flexible members secured to said sheaves for winding movement thereon reversely to the winding movement 55 of said flexible connections, and springs attached to the outer ends of said flexible member.

In testimony whereof I hereunto affix my signature.

CLARENCE A. MENTZER.
